BUTTER DISH

Alfred K. Hauser, 4034 N. Kolmar Ave., Chicago, Ill.

Filed Jan. 9, 1961, Ser. No. 63,492

Term of patent 14 years

(Cl. D44—5)

Fig. 3.

FIG. 1 is an elevational view of a butter dish showing my new design;

FIG. 2 is a top plan view thereof; and

FIG. 3 is an elevational view partly in section of the container with the cover removed.

The bottom of the vessel for the butter dish of my new design is recessed as shown, partially in cross-section in FIG. 3.

I claim:

The ornamental design for a butter dish, as shown.
